UNITED STATES PATENT OFFICE.

DON ALONZO SANFORD, OF WASHINGTON, DISTRICT OF COLUMBIA; GRETA L. SANFORD ADMINISTRATRIX OF THE SAID DON ALONZO SANFORD, DECEASED.

SAFETY LOCKING DEVICE FOR ELEVATORS.

Application filed August 1, 1921, Serial No. 489,040. Renewed April 19, 1924.

To all whom it may concern:

Be it known that I, DON ALONZO SANFORD, a citizen of the United States, and a resident of Washington, in the District of Columbia, have invented certain new and useful Improvements for Safety Locking Devices for Elevators, of which the following is a specification.

My invention relates to safety locking devices for elevators of the character employed in the safety locking apparatus embodied in my co-pending application filed December 10, 1920, Serial No. 429,628.

The purpose of my present invention is the provision of a safety locking device for elevators which operates in such a manner to insure of the landing door being closed before it is possible to start the elevator, my invention being of extremely simple, durable and inexpensive construction, and easily applied to doors of elevators of standard construction.

I will describe one form of device embodying my invention and will then point out the novel features thereof in claims.

In the accompanying drawings:

Figure 1 is a view showing in perspective one form of locking device embodying my invention.

Figure 2 is a view showing in front elevation the locking device shown in Figure 1 with the cover plate removed.

Figure 3 is an enlarged perspective view of the device shown in the preceding views with the releasing member and adjacent parts disassembled with respect to the casing of the device.

Figure 4 is a vertical sectional view taken on the line 4-4 of Figure 2 showing the cover in position and the releasing member or plate in releasing position.

Similar reference characters refer to similar parts in each of the several views.

Referring specifically to the drawings, my invention in its present embodiment comprises a casing K preferably formed of non-magnetic material and including a cover C which is adapted to close the open side of the casing as will be understood. The end walls of the casing K are formed with slots 15 in which pivot pins 16 are adapted to rotate for pivotally supporting a releasing member designated generally at M. The releasing member is mounted for movement within the casing K as illustrated to ad-

vantage in Figure 4, and this member comprises a rectangular plate 17 formed of highly magnetic material and carrying pins 18 at its vertical edges so as to be capable of being locked transversely of the casing. This releasing member M is designed to control the movement in one direction of the locking lever L which, as shown in Figure 3, is fulcrumed intermediate its ends upon a pin 18 fixed within the casing K at a point directly above the slot 19 formed in the lower wall of the casing and in such manner that the lower end of the lever at all times projects through the slot and exteriorly of the casing. The lever L is formed at its lower end with an operating lip 20, and a locking lip 21, the latter of which is spaced from and preferably disposed at an angle to the operating lip. The opposite or upper end of the lever L is provided with a lug 22 adapted to seat within an opening 23 formed in the plate 17 of the releasing member M and at such point that the lug is disposed within the opening when the lever is in the position shown in Figure 2. This position of the lever L, I term the locking position as in this position it is adapted to effect the locking of the landing door in closed position.

This position of the lever is defined by a stop pin 24 projecting from the inner side of the rear wall of the casing K in the manner shown in Figure 3. The lever is also capable of occupying another extreme position wherein it engages a stop pin 25, and the lever is normally urged to this position by means of the coiled contractile spring 26 secured to one end of the lever by a screw 27 and at the opposite end to the casing by a screw 28. However, this spring may be omitted, as the opening of the door will turn the lever to its released position adjacent the stop pin 25, as is obvious. This position of the lever I term the releasing position, as in this position the landing door can be moved to open position or is open.

As shown in Figure 4, the releasing member M is sustained within the casing K between the lever L and the cover plate C, this member being normally urged away from the cover plate by coiled expansible springs 29 (Figs. 2 and 3) mounted in annular bosses 30 formed in the plate 17 and having closed inner ends formed with bearing surfaces for the end of the springs. The

opposite ends of the springs bear against the inner side of the cover plate so that by this arrangement the plate 17 is normally urged rearwardly toward the lever L. In this urged position of the releasing member M, the locking lug 22 is adapted to seat within the opening 23 when the lever L is in the locking position shown in Figure 2 so that normally the locking device operates to effect the locking of the landing door.

As in the safety locking apparatus embodied in my co-pending application, the present locking device is provided with a circuit controller operated by the releasing member and adapted to control the supply of current to elevator operating motors. This circuit controller in the present instance comprises a pair of stationary contacts 31 arranged between plates of insulating material 32 with the latter formed with circular openings in the manner clearly shown in Figures 3 and 4 to expose the contacts and to permit of their being bridged by a movable contact 33. The contact 33 is in the form of a ring loosely fitted on a stud 34 secured to a plate of insulating material 35 carried by the plate 17. The contact 33 is locked against displacement in the stud 34 by a cotter pin 36, with a coiled expansible spring 37 embracing the stud and interposed between the plate 35 and the contact 33 so as to normally bias the contact into engagement with the cotter pin. This arrangement permits of a yielding movement of the contact 33 when the plate 17 is moved so that the stud passes into the openings of the plates 32 with the contact engaging stationary contacts 31. The arrangement of the circuit controller is such that with the releasing member M in this normal position the contact 33 bridges the contacts 31 so that the circuit to the controller is closed. The contacts 31 constitute the terminals of the power circuit for supplying power to the motors for operating the elevator, although in the present instance this showing has been omitted as the circuit forms no part of the present invention.

In the operation of the locking device the locking lever L is adapted to be sustained on the elevator shaft or hatchway directly above the landing or hatchway door HD, and the latter is adapted to carry a locking finger designated at F, in the path of movement of which is interposed the lower end of the lever. The arrangement of the locking device with respect to the door is such that when the door is moved from closed to open position the locking finger F travels in the direction of the arrow in Figure 2 engaging the locking lip 21 and thus swinging the lever L from the locking position shown in Figure 2 to the releasing position shown in Figure 3. As the releasing member normally occupies a locking position with

respect to the lever L, it will be clear that the lever can only be moved to releasing position when the releasing member occupies a releasing position. To move the releasing member to releasing position, an electro-magnet E is provided which is adapted to be carried by the elevator and so positioned thereon that when the elevator is at or adjacent to a floor landing and the electro-magnet energized its magnetic field will traverse the releasing member, the arrangement of the locking device and electro-magnet being better illustrated in my co-pending application hereinbefore referred to. To reduce the current necessary to energize the magnet E sufficiently to actuate the releasing member, the cover plate C is formed with slots 38 as clearly shown in Figure 1, such slots being arranged so that they will expose the releasing member at points defining the path of movement of the poles of the magnet E across the face of the casing thereby reducing the reluctance and thus permitting of the more ready passage of the magnetic lines of force from the magnet to the releasing member.

In Figures 1 and 2 I have shown projecting pieces or bars 39 of highly magnetic material integral with or attached to the surface of the plate 17, also of magnetic material, part of each of these projecting pieces being adapted to extend through the slot 38 in the casing cover C when the releasing member is in an unlocking position and attracted by the electro-magnet.

In operation, the locking finger F occupies the position shown in Figures 1 and 2 when the elevator door is closed, and the locking lever L is in locking position with the lug 22 within the opening 23. As previously described the circuit controller is closed when the releasing member is in locking position so that current can be supplied to the motors for operating the elevator. When the elevator reaches a landing and it is desired to open the landing door, the electro-magnet E being energized forces the releasing member forwardly to the position shown in Figure 4 so that the lug 22 is withdrawn from the opening 23. As soon as this occurs the door may be opened, and a slight movement of the door displaces the locking lever L and prevents the lug 22 from again entering the opening 23 until the door is entirely closed again. Simultaneously with this operation the circuit controller is also opened thus preventing movement of the elevator while the door is open. When returning the door to closed position, the locking finger F engages the operating lip 20 and thus moves the locking lever back to locking position, the movement of the elements being such that the door must be completely closed before the lug 22 is opposite the opening 23. The electro-magnet E is

adapted to be deenergized as soon as the circuit controller is open so that when the locking lever returns to locking position the releasing member is free to return to locking position under the action of the springs 5 29, it being understood that the lug 22 is now opposite the opening 23. When the releasing member is returned to locking position the circuit controller is closed thus permitting 10 the operation of the elevator. From this operation it will be seen that the operation of the elevator can be effected only after the door has been completely closed as it is necessary that the locking lever be completely returned to its locking position before the releasing member can move to locking position.

Should it be necessary to open the door when the elevator is not adjacent the landing so that the electro-magnet can not operate the releasing member, the latter can be manually moved to releasing position through the medium of a crank or handle H secured to the projecting end of one of the 25 pins 16.

Although I have herein shown and described only one form of safety locking device embodying my invention, it is to be understood that various changes and modifications may be made herein without departing from the spirit of the invention or the spirit and scope of the appended claims.

What I claim is:

1. A locking device for elevator hatchway doors comprising a locking member movable to occupy locking and releasing positions, an operating member carried by a hatchway door and movable to engage said locking member for moving the latter to either of its 35 positions, a releasing member movable to occupy a locking position in which said locking member is secured in locking position, and also movable to a releasing position in which said locking member is free to be moved by the operating member on the door, means for normally urging the releasing member to a locking position, and a main 40 electrical circuit controller operable by said releasing member in a manner to effect closing or opening thereof according as the releasing member occupies locking and releasing positions.

2. The subject-matter of claim 1 wherein the releasing member is of magnetic material, with the addition of an electro-magnet adapted to be carried by an elevator car for moving said releasing member from a locking to a releasing position and opening the main circuit.

3. The subject-matter of claim 1 wherein the locking member and the releasing member are movable and provided with interlocking means, whereby in one of their relative positions the locking member is locked and the main circuit closed and in another

of their relative positions the releasing member is in a releasing position and the main circuit opened.

4. The subject-matter of claim 1 wherein the locking member and releasing member 70 are provided with a lug on one of said members and an opening or seat formed in connection with the other member, so that in one of their relative positions they will interlock and in another relative position the 75 releasing member will be locked in a releasing position and the main circuit opened.

5. A locking device for elevator doors comprising a casing containing a locking member and a releasing member of magnetic material, an electro-magnet outside the casing adapted to be carried by an elevator car and, when moved to a position adjacent the said releasing member and energized, move the said releasing member from a locking to a released position, a door with an operating member, and mechanical means co-operating with said releasing member and locking member to lock said releasing member in a released position when the door 90 is open.

6. The subject-matter of claim 5 wherein the said mechanical means consists of a lug carried by the locking member, said lug in one position of the locking member being within a hole in the releasing member and in another position engaging the releasing member and locking it in its releasing position.

7. A locking device for elevator hatchway doors, comprising in combination a locking lever movable to occupy locking and releasing positions, a hatchway door, a locking finger carried by the door and movable to engage said lever for moving the latter to either of its positions, a releasing member to occupy a locking position in which said locking lever is secured in locking position and a releasing position in which said lever is free to be moved by the locking finger, means for urging the releasing member to locking position, and a circuit controller operable by said releasing member in a manner to effect closing or opening thereof according as the releasing member occupies locking and releasing positions, said releasing member co-operating with the locking lever to permit the return of the releasing member only when the locking lever is in complete locking position.

8. A locking device for elevator hatchway doors, comprising in combination a casing including a cover provided with a slot, a locking lever fulcrumed in the casing, said lever being capable of occupying locking 125 and releasing positions, a lug carried by the lever, and a releasing member movable within the casing to occupy locking and releasing positions; an opening being formed in the member and arranged to receive said 130

lug when the lever and member are in locking positions, and said releasing member being disposed so that said slot in the cover exposes a portion of the member when normally urged to locking position.

9. A locking device for elevator hatchway doors, comprising in combination a casing including a slotted cover, a locking lever fulcrumed within the casing to occupy locking and releasing positions, a releasing member of magnetic material capable of occupying locking and releasing positions and arranged to have portions thereof exposed by the said slots, and springs arranged between said cover and releasing member to normally urge the member to locking position.

10. The subject-matter of claim 9 wherein said releasing member is provided with 20 pieces or bars 39 of highly magnetic material.

11. The subject-matter of claim 9 wherein said cover is of non-magnetic material.

12. The subject-matter of claim 9 where- 25 in the casing is provided with stops to limit the movements of the locking lever.

13. The subject-matter of claim 9 where- 30 in said releasing member is provided with a handle located outside the casing.

14. The subject-matter of claim 9 where- 35 in the locking lever and the releasing mem- ber are pivoted to the casing in different planes.

15. A locking device for elevator hatch- 40 way doors, comprising a casing including a cover formed of non-magnetic material, a locking lever fulcrumed within the casing to occupy locking and releasing positions, a lug carried by the lever, a releasing member capable of occupying locking and releasing positions, bushings formed on the releasing member, springs mounted within the bushing and arranged between said cover and member to normally urge the member to locking position, an opening formed in the member and arranged to receive said lug when the releasing member and the lever are in locking positions, and a circuit controller 45 operable by the releasing member to effect closing or opening thereof according as the member occupies locking or releasing position.

16. A locking device for elevator hatch- 50 way doors, comprising in combination a cas- ing including a cover formed of non-magnetic material, a locking lever fulcrumed within the casing to occupy locking and releasing positions, a lug carried by the lever, a releasing member capable of occupying locking and releasing positions, springs ar- 55 ranged between said cover and member to normally urge the member to locking position, an opening formed in the member and arranged to receive said lug when the re- 60 leasing member and the lever are in locking

positions, and a circuit controller operable by the releasing member to effect closing or opening thereof according as the member occupies locking or releasing position, said circuit controller comprising a stud carried 70 by the member, a movable contact mounted on the stud, a spring engageable with the contact for yieldingly holding the same in a definite position on the stud, and spaced contacts mounted on and insulated from the 75 casing and adapted to be bridged by the movable contact.

17. A locking device for elevator hatch- 80 way doors, comprising a locking lever mov- able to occupy locking and releasing posi- 85 tions, a releasing member movable to occupy locking and releasing positions in respect to the lever when said lever occupies the aforesaid respective positions, and cir- 90 cuit controlling means associated with the releasing member adapted to be closed when the locking positions are assumed and opened when the releasing positions are as- 95 sumed.

18. An elevator lock comprising a locking 100 lever, means on which it is pivoted to rock in one plane, means on an elevator hatch- 105 way door to move said lever into a locking position, a releasing member pivoted to rock in another plane and occupy locking and releasing positions in respect to said locking lever and thus correspond to the respective 110 positions of said lever, and circuit controlling means associated with said releasing member adapted to be closed when both the 115 lever and releasing member occupy the locking 120 positions.

19. An elevator lock comprising a locking 125 lever, means adapted to be carried by an ele- 130 vator door to move the lever to a locking po- 135 sition, a releasing member co-operating with the lever, circuit controlling means associated with the releasing member, means carried by an elevator and adapted to with- 140 draw the releasing member from a locking 145 engagement with said lever and at the same 150 time break said circuit controlling means, and means associated with the releasing member to move it back into a locking po- 155 sition on said lever when the lever is in a corre- 160 sponding position and at the same time re- 165 establish the circuit of said controller.

20. An elevator lock comprising a piv- 170 tally mounted locking lever with a lug, and a releasing member adapted to assume locking and releasing positions in respect to 175 said lever, having an opening to receive the lug when the lever and member are in lock- 180 ing positions, said lug engaging a solid por- 185 tion of the member when the lever is in the releasing position, thereby preventing said member from moving to a locking position.

21. An elevator lock comprising a piv- 190 tally mounted locking lever with a lug, a 195 releasing member adapted to assume lock-

ing and releasing positions in respect to said lever, having an opening to receive the lug when the lever and member are in the locking positions, said lug engaging a solid portion of the member when the lever is in the releasing position, thereby preventing said member from moving to a locking position, and circuit closing means which is controlled by the positions of said releasing member.

5 22. An elevator lock having a casing, a re-

leasing member pivotally mounted in the casing, circuit controlling means associated with the releasing member and towards which said member is adapted to swing, resilient means situated between parts of the ¹⁵ casing and said member to produce said swinging, and means to retain said resilient means in place.

DON ALONZO SANFORD.
